UNITED STATES PATENT OFFICE.

WILLIAM C. PRESNELL AND BIRD N. WHITAKER, OF PILOT MOUNTAIN, NORTH CAROLINA, ASSIGNEES OF ONE-THIRD TO WILLIAM R. BADGETT, OF PILOT MOUNTAIN, NORTH CAROLINA.

PLOW.

Application filed July 10, 1924. Serial No. 725,176.

To all whom it may concern:

Be it known that we, WILLIAM C. PRESNELL and BIRD N. WHITAKER, citizens of the United States, residing at Pilot Mountain, 5 in the county of Surry and State of North Carolina, have invented new and useful Improvements in Plows, of which the following is a specification.

Our invention relates to improvements in 10 plows, the objects in view being to provide a strong and durable plow in which the height of the handles may be adjusted to suit the plowman, and also in which the standard may be adjusted so as to regulate the depth 15 of cut.

Another object of invention is to provide a shovel plow in which the standard is capable of angular adjustment in relation to the beam without causing any play or weak 20 points in such adjusting devices.

A brief description of the drawings follows:

Figure 1 is a perspective view of the plow.

Figure 2 is a longitudinal sectional view 25 of the rear portion of the plow.

In the drawings like numerals of reference indicate like parts thruout the figures.

The numeral 10 designates the beam of the plow to which is affixed the iron strap 11. 30 This iron strap 11 is secured to the forward end of the beam by the bolt 12 and extends forwardly, downwardly, and rearwardly to the underneath side of the beam, and is there secured by the other end of the bolt 35 12 which passes thru the beam 10, thus forming the clevis 13. This iron member 11 extends rearwardly the entire length of the beam 10, and extends upwardly as at 14, and forwardly at 15, which portion is embedded in a groove in the upper side of the 40 rear end of the beam 10. If desired, the iron member 11 may extend forwardly from the point 15 to the forward end of the beam 10 and join the other end of the iron member at 12, thus going completely around the beam 10.

Adjustably connected to the beam 10 is the standard comprising the members 16 and 17. These members are located on either 50 side of the beam 10 and extend downwardly and are welded together at the base portion thereof. The members 16 and 17 have holes therein at points above and below the

beam, and bolts 17 and 18 are placed therein to secure the standard to the beam. The 55 bolt 18 penetrates the eye 19 of the member 20 and forms a hinge. This member 20 is located between the upper ends of the standard members 16 and 17, and extends rearwardly, having holes 21 therein which 60 serve to receive the bolt 22 for purposes of adjusting the standard with respect to the beam.

The brace 23 is secured to the lower portion of the bolt 22 and extends forwardly 65 and downwardly to a point between the standard members 16 and 17, and is there secured to the standard by means of a bolt 24.

The member 25 is secured to the lower 70 side of the beam 10 by means of the screws 33, thus forming a slot 36 in which the bolt 17 slides.

The handles 26 are secured to the forward portion of the beam by the cuff-bolt 27. 75 The rearward portion of the handles are secured by members 28 to the rear end of the beam by the bolt 29, and at the upper ends of the braces 28 there are holes 32, thru which bolts 30 are inserted to secure the 80 braces 28 to the handles.

One or more bolts 31 penetrate the beam 10 and the iron strap 11 to thus hold the member 11 in close relation to the beam 10.

In the rear end of the beam 10 there is a 85 hole 34 thru which the bolt 29 is placed to secure the braces 28 to the rear portion of the beam 10.

Between the beam 10 and the member 20 there is a space 35 which is enlarged or decreased upon adjustment of the standard 16-17 by moving the member 20 rearwardly or forwardly. Without this space the bolts 17 and 18 would bind on the upper and lower edges of the beam and thus prevent 95 adjustment of the angularity of the standard with respect to the beam 10.

The space or slot 36 accommodates the bolt 17 and prevents up and down movement of the standard.

The method of operation is as follows:

To adjust the angularity of the standard, the nut is removed from the bolt 22 and the member 20 is moved forwardly or rearwardly until another of the holes 21 will register 105 with the bolt 22. This increases or decreases

the depth of cut of the plow. The bolt 24 is loosely mounted in the brace 23 and allows the adjustment above described.

From the above detailed description it will be seen that we have devised a plow in which the angularity of the standard can be changed, and at the same time means are provided whereby this means of adjustment does not weaken the plow, but on the 10 other hand results in a plow which is strong and durable.

Having thus described our invention what we claim is:

1. In a plow, a beam, a standard, means 15 for adjusting the angular relation between the beam and standard, said means comprising a member pivotally secured to the upper portion of the standard, and adjustably secured to the beam, a guard member secured 20 to the lower side of the beam, and off-set from the beam forming a slot in which an element secured to the standard slides.
2. In a plow, a beam, a standard, said standard comprising members located on 25 each side of the beam, and extending downwardly to a point where they converge and are inseparably united, a bolt connecting the standard members above the beam, another bolt connecting said members immediately

below the beam, a slot on the lower side of 30 the beam formed by an off-set member thru which the lower bolt passes, and means for adjusting the angular relation between the beam and the standard.

3. In a plow, the combination of a beam, 35 a standard, and means for adjusting the angularity between the beam and the standard, said means comprising a member pivoted to the top portion of the standard in spaced relation to the beam, and means located on the lower side of the beam and off-set therefrom to prevent a decrease in said spaced relation apart from a change in the angularity between the beam and standard.

4. In a plow, the combination of a beam, 40 a standard, and means for angular adjustment of the standard, said means being connected to the upper portion of the standard in spaced relation to the beam, and an off-set guard member on the lower side of the 45 beam to prevent a downward movement of the standard.

In testimony that we claim the foregoing as our own we have hereto affixed our signatures.

WILLIAM C. PRESNELL.
BIRD N. WHITAKER.
